UNITED STATES PATENT OFFICE.

WALTER P. COLEMAN, OF ATLANTA, GEORGIA.

MEANS FOR OPERATING VIBRATING CHURNS.

No. 857,923.

Specification of Letters Patent.

Patented June 25, 1907.

Application filed April 29, 1907. Serial No. 370,926.

To all whom it may concern:

Be it known that I, WALTER P. COLEMAN, a citizen of the United States, residing at Atlanta, in the county of Fulton and State 5 of Georgia, have invented certain new and useful Improvements in Means for Operating Vibrating Churns; and I do hereby declare the following to be a full, clear, and exact description of the invention, such as will 10 enable others skilled in the art to which it app pertains to make and use same, reference being had to the accompanying drawings, and to the letters and figures of reference marked thereon, which form a part of this 15 specification.

This invention relates to new and useful improvements in apparatus for operating churns and the object in view is to produce a simple and efficient apparatus whereby 20 either hand or foot power may be utilized for operating the dasher, the adjusting means being simple and readily accomplished.

My invention comprises various details of construction and combinations and arrangements of parts which will be hereinafter 25 fully described and then specifically defined in the appended claims.

I illustrate my invention in the accompanying drawings, in which:—

30 Figure 1 is a perspective view of the apparatus and Fig. 2 is a detailed view, a portion of the same being shown in section and illustrating the manner in which the dasher is held in place.

35 Reference now being had to the details of the drawings by letter, A designates a standard rising from a plate B. C designates a churn body having a dasher D therein, the upper end of which dasher is mounted in a 40 suitable bearing in the horizontally disposed arm F of said standard. Rising from the base plate B is a post G having a metallic strap H fixed to one side thereof, between which and the post the foot tread K is guided in its vertical movement, said foot tread being 45 pivotally connected at its opposite end to the pin N carried by said standard.

Mounted upon the top of the post is a pin O upon which the grooved wheel Q is journaled 50 and Q' is a handle provided for the purpose of rocking said wheel upon its pivotal pin O. Said arm F, which is made preferably of a flexible material, is adapted to yield to allow the wheel to be placed over the pivot pin O and serves to retain the same in place 55 thereon. R designates a rope which winds

about the dasher shaft and also passes about the grooved wheel Q and is provided for the purpose of imparting a rotary movement to the dasher when the wheel Q is rocked upon its pivot pin. S designates a pulley journaled upon a pivot S' carried by the said standard and T is a rope, one end of which is fastened to the face of the wheel at T', said point of connection of the rope T with the 60 said wheel being eccentric, whereby, as the rope is pulled upon, a rotary movement may be imparted to the wheel Q. A spring W is fastened at one end to said standard and its other end to the circumference of said wheel, 65 the purpose of which spring is to cause the wheel to be returned to its normal position after having been rotated in one direction by pulling upon the rope T. Said tread member is provided with a slot K', one end 70 of which is contracted and is adapted to receive the rope T having knots T² formed near its free end, which knots are adapted to engage the under edge of the tread about the marginal edge of the contracted portion of 75 the slot to hold the same in an adjusted position.

In operation, when it is desired to actuate the mechanism by hand, the knotted end of the rope is detached from the slot in the 80 tread member and the rope removed from the pulley S and also the spring W is detached from the wheel, thereby leaving the apparatus free to be operated from the swinging lever Q'. Should it be desired to operate the 85 apparatus by tread power, the rope is positioned in the manner shown in Fig. 1 of the drawings and, by the depression of the tread lever, the wheel will be rotated in one direction and returned to its normal position by 90 means of said spring.

From the foregoing, it will be noted that, by the provision of the device shown and described, a simple and efficient means is afforded for operating the dasher of a churn 95 either by foot or hand power, as may be desired.

What I claim is:—

1. An apparatus for operating rotary dasher churns, comprising, in combination, a 100 base and a standard rising therefrom, a churn mounted upon said base, a dasher therein, a laterally projecting arm in which the upper end of said dasher has a bearing, a post rising from said base, a pivot pin at the upper end 105 of said post, a horizontally journaled grooved wheel pivotally mounted upon said pin, a
